UNITED STATES PATENT OFFICE.

ROBERT HEAD, OF NEW YORK, N. Y., ASSIGNOR TO THE AEOLIAN COMPANY, A CORPORATION OF CONNECTICUT.

PHONOGRAPH WITH EXTENSIBLE HORN.

1,326,729.

Specification of Letters Patent.

Patented Dec. 30, 1919.

Application filed June 23, 1916. Serial No. 105,373.

To all whom it may concern:

Be it known that I, ROBERT HEAD, a citizen of the United States, residing at New York, in the county and State of New York, 5 have invented certain new and useful Improvements in Phonographs with Extensible Horns, of which the following is a specification.

My present invention relates to a phonograph with an extensible horn, the features 10 and advantages of which will be apparent to those skilled in the art from an understanding of the following description in connection with the drawings, showing one 15 of the specific embodiments my invention may take.

In the drawings Figure 1 is a vertical section partly in side elevation of a cabined phonograph embodying my invention and 20 showing the horn extended; Fig. 2 is a horizontal section partly in plan taken below the motor-board in Fig. 1; Fig. 3 is a vertical section through the front portion of the instrument showing the mouth-section of the 25 horn telescoped back into the cabinet; Fig. 4 is a partial face view of the door-portion of the cabinet, the left hand portion of the doors being broken away to disclose the mouths of the two horn-sections; Fig. 5 is 30 an enlarged vertical section partly in elevation to show the structure of the door-locking means; Fig. 6 is a vertical sectional view indicating the relationship between the horn-sections when sliding on each other; 35 Fig. 7 is the same indicating their relationship when interlocked; and Fig. 8 is a partial plan view of the interlocked horn-sections partly in horizontal section.

Describing now the devices of the drawings:—1 is a phonograph cabinet, 2 the sound-box and tone arm, 3 the deck or motor-board, 4 the turn-table, and 5 the motor. The horn consists of a main section 6 within the cabinet and a mouth-section 7 outside 45 but adapted to be telescoped into the cabinet when not in use. The mouth section is mounted in a box-like frame 8 sliding in a rectangular opening in the front of the cabinet. 9 is a tail-piece extension (Figs. 50 1 and 2) from said frame sliding through an opening 10^a in cross-bar 10 in the cabinet to prevent the front of the mouth-section and its frame 8 from dropping or sagging as it is withdrawn from the cabinet and

also to guide said mouth-section to prevent 55 it from jamming as it is slid in and out.

The main horn section has rearwardly turn-backed flanges 11 at its mouth which are divided from each other at the corners so as to be springy and form a tight fit 60 when received into a collar-like extension 12 on the back of the mouth-section 7. This collar has an inwardly directed flange 13 preventing the mouth-section from being pulled away from or off the main-section. 65

The bottoms of the two horn sections are substantially parallel to the sliding direction of the mouth-section. In other words, in the particular embodiment shown, they are flat and ordinarily would slide in contact with 70 each other so that the bottom of the mouth-section would soon become scratched up and rendered unsightly. This I avoid by so locating the horn-sections relatively to each other that their bottoms are out of contact, 75 while the mouth-section is being slid in and out. On the other hand, the collar 12 is so inclined to the flanges 11 that they co-operate, when the mouth-section is forced into out-position, not only to make a tight joint 80 between themselves but also lift the bottom of the mouth-section into snug contact with the bottom of the main section. In short the joint between the two horn sections is rendered tight all around to the improvement of the acoustic quality of the total horn. 85

It will be further noted that the joint made by the parts 11 and 12 between the horn-sections is such (see Fig. 7) that the 90 sides of the mouth-section continue the sides of the main-section without any abruptness in the joint—which again is to the improvement of the acoustic quality of the total horn. 95

When the mouth-section is in its out-position, means is provided for releasably locking it in that position as follows:—14 is a piece having its front end pivoted at 15 to the frame 8 of the mouth-section and a recess 16 on its rear-end adapted to have a wedge-action when pulled down into side contact with a fixed pin 17 (cf. Figs. 1 and 2) projecting inwardly from the side of the cabinet. This locks the mouth section in its 105 out-position and forces into tight relationship the parts constituting the joint between the two horn-sections. The parts 14, 15 and 100

17 are duplicated on both sides of the horn; and both pieces 14 have downwardly extending operating-arms 18 united at their ends by a cross-rod 19. 20 is a rod slidably supported on the bottom of the frame 8, its inner end being pivotally connected with the cross-rod 19 and its outer end being provided with a hand-piece or knob 21 (see Figs. 1 and 2). When the mouth-section is locked rigidly in out-position as shown in these figures and it is desired to release the locked union between the horn-sections and telescope the mouth section back into the cabinet, this is simply accomplished by pushing inwardly the knob 21 because this tilts upwardly the pieces 14 until their bottom edges clear the tops of the pins 17, whereupon continued pushing on the knob slides the mouth-section back into the cabinet. Reversely pulling outwardly on this same knob 21, pulls out the mouth-section of the horn and when in its out-position, the final pull on the knob wedges the ends 16 of the pieces 14 down against the pins 17 which forces and locks together the two horn-sections with a tight joint, as described, between them.

The frame of the mouth-section has a rectangular opening in it corresponding to the mouth of said section, and carries a door 22 (Figs. 1 and 4) hinged to it at 23. This door 22 is compound, in that it embodies a second smaller door, illustrated as a grille 24, adapted to be independently opened on its own hinges 25 (Figs. 3 and 4) to leave an opening corresponding to the mouth of the main horn section. The surrounding part of the door 22 being closed while the grille is open (compare Fig. 3) eliminates unsightliness by preventing looking into the cabinet outside the main horn.

Finally automatic door-locking means is provided whereby when the horn-sections are extended as in Fig. 1, pulling on the door-knob 26 will open the entire compound-door as a unit because the grille door 24 is then automatically locked in the frame 22 so that the two must carry together. This therefore opens up the full mouth of the mouth-section of the horn which is just what is wanted when this section is in use. On the other hand, when the mouth-section is telescoped into the cabinet out of use, the door frame 22 is thereby automatically locked in shut position, so that pulling on the same door-knob 26 (cf. Fig. 3) can only open the grille-door 24, which is just what is wanted because this opens up the mouth of the main horn-section which is now alone in use.

The detail means by which I accomplish this is shown in one of its forms in Fig. 5. As shown, the top-board of the frame 8 of the mouth-section, the door frame 22, and the top of the grille-door 24, all contain aligned vertical holes housing respectively

the upwardly spring-pressed plunger 27, the plunger 28 retained in position by the projection 29, and the upwardly spring-pressed plunger 30. When the mouth-section is housed within the cabinet out of use, the plunger 27 is forced down by its contact with the top of the cabinet-opening so that its lower end enters the mouth of the hole in door-frame 22 as in Fig. 5 preventing it from being opened by pulling on the door-knob 26, which accordingly opens only the grille door 24. On the other hand, when the mouth-section is out, the plunger 27 springs upwardly, unlocks the door-frame 22. Further this permits the plunger 28 to rise under the lifting action of the spring-pressed plunger 30 whose nose therefore enters the hole in the door-frame 22, thereby locking together said frame and the grille-door so that they now carry as one door to open the large mouth of the extended horn.

What I claim is:—

1. In a phonograph, the combination of a cabinet, a horn comprising a mouth-section and a main section, the main section being located inside the cabinet, and the mouth section outside but being telescopicable into the cabinet when not in use, the mouth section in out-position being adapted when forced outwardly to form a substantially tight joint with the main section, and releasable means for forcing the mouth section outwardly as aforesaid.

2. In a phonograph, the combination of a cabinet, a horn comprising a mouth-section and a main section, the main section being located inside the cabinet, and the mouth section outside but being telescopicable into the cabinet when not in use, said horn-sections having flanges adapted to coact to form a substantially tight joint between them when the mouth-section is in its out-position and is forced outwardly, and releasable means coöperative with the opposite sides of said mouth section for forcing the mouth section outwardly equally at opposite sides thereof to produce uniform engagement of said flanges, as aforesaid.

3. In a phonograph, the combination of a cabinet, a horn comprising a mouth-section and a main section, the main section being located inside the cabinet, and the mouth section outside but being telescopicable into the cabinet when not in use, and joining means between the main horn-section and the mouth section in its out-position comprising an external turned-back flange at the mouth of the main section received into a collar-like extension on the rear-end of the mouth section.

4. In a phonograph, the combination of a cabinet, a horn comprising a mouth-section and a main section, the main section being located inside the cabinet, and the mouth section outside but being telescopicable into

the cabinet when not in use, and joining means between the main horn-section and the mouth section in its out-position comprising an external turned-back flange at 5 the mouth of the main section received into a collar-like extension on the rear-end of the mouth section, the flange on the main section being circumferentially discontinuous to make the sections springy so that 10 when telescoped into the collar there is a tight joint between the two.

5. In a phonograph, the combination of a cabinet, a horn comprising a mouth-section and a main section, the main section being 15 located inside the cabinet, and the mouth section outside but being telescopic into the cabinet when not in use, and joining means between the main horn-section and the mouth section in its out-position comprising an external turned-back flange at the 20 mouth of the main section received into a collar-like extension on the rear-end of the mouth section, the flange on the main section being springy in a direction transversely of the telescoping movement of the 25 mouth section so that when telescoped into the collar there is a tight joint between the two sections, and an inwardly directed flange on the rear end of the collar-like extension adapted to engage the rear edge of 30 said turned back flange and thus prevent the mouth-section from being pulled off the main section.

6. In a phonograph, the combination of a cabinet, a horn comprising a mouth-section and a main section, the main section being 35 located inside the cabinet, and the mouth section outside but being telescopic into the cabinet when not in use, and joining means between the main horn-section and the mouth section in its out-position comprising an external turned-back flange at the mouth of the main section received into a collar-like extension on the rear-end of the 40 mouth section, the bottoms of the two sections being substantially parallel with the telescoping movement of the mouth-section, said horn-sections being mounted so that their bottoms do not contact with each other 45 as the mouth section is slid in and out, and the turned-back flange being adapted to cooperate with the collar so as to bring the bottoms of the two sections into contact when in their extended position.

55 7. In a phonograph, the combination of a cabinet, a horn comprising a mouth-section and a main section, the main section being located inside the cabinet, and the mouth section outside but being telescopic into 60 the cabinet when not in use, and joining means between the main horn-section and the mouth section in its out-position comprising an external turned-back flange at the mouth of the main section received into 65 a collar-like extension on the rear-end of the

mouth section, the flange on the main section being circumferentially discontinuous to make the sections springy so that when telescoped into the collar there is a tight joint between the two, the bottoms of the two 70 sections being substantially parallel with the telescoping movement of the mouth-section, said horn-sections being mounted so that their bottoms do not contact with each other as the mouth section is slid in and out, and the turned-back flange being adapted 75 to coöperate with the collar so as to bring the bottoms of the two sections into contact when in their extended position.

8. In a phonograph, the combination of a cabinet, a horn comprising a mouth-section and a main section, the main section being located inside the cabinet, and the mouth section outside but being telescopic into the cabinet when not in use, the bottoms of 80 the two sections being substantially parallel with the telescoping movement of the mouth-section, said horn-sections being mounted so that their bottoms do not contact with each other as the mouth section is 85 slid in and out, the front of the main section being adapted to act on the rear of the mouth section when in out-position to bring their bottoms into contact and otherwise make the two sections circumferentially 90 snug.

9. In a phonograph, the combination of a cabinet, a horn comprising a mouth-section and a main section, the main section being 100 located inside the cabinet, and the mouth section outside but being telescopic into the cabinet when not in use, the bottoms of the two sections being substantially parallel with the telescoping movement of the mouth-section, said horn-sections being 105 mounted so that their bottoms do not contact with each other as the mouth section is slid in and out, and means for making the two sections circumferentially snug when in their extended position.

10. In a phonograph, the combination of a cabinet, a horn comprising a mouth-section and a main section, the main section being located inside the cabinet, and the mouth section outside but being telescopic 115 into the cabinet when not in use, the bottoms of the two sections being substantially parallel with the telescoping movement of the mouth-section, said horn-sections being mounted so that their bottoms do not contact with each other as the mouth section is 120 slid in and out.

11. In a phonograph, the combination of a cabinet, a horn comprising a mouth-section and a main section, the main section being located inside the cabinet, and the mouth section outside but being telescopic into the cabinet when not in use, means for releasably locking the mouth-section in its out-position, and a hand-piece for sliding the 130

mouth-section in and out, said hand-piece being operatively connected with said locking means.

12. In a phonograph, the combination of 5 a cabinet, a horn comprising a mouth-section and a main section, the main section being located inside the cabinet, and the mouth section outside but being telescopicable into the cabinet when not in use, means for 10 releasably locking the mouth-section in its out-position, and a hand-piece for pulling the mouth-section into its out-position and pushing it back again, said hand-piece being operatively connected with the locking 15 means to put it into action on the pulling stroke and to release it on the pushing stroke.

13. In a phonograph, the combination of 20 a cabinet, a horn comprising a mouth-section and a main section, the main section being located inside the cabinet, and the mouth section outside but being telescopicable into the cabinet when not in use, and means for preventing the front of the mouth section from dropping as it is pulled out and 25 for guiding said mouth-piece comprising a tail-piece projecting rearwardly from said section into the cabinet held down and laterally guided by a stationary part in the 30 cabinet.

14. In a phonograph, the combination of 35 a cabinet, a horn comprising a mouth-section and a main section, the main section being located inside the cabinet, and the mouth section outside but being telescopicable into the cabinet when not in use, means preventing 40 the mouth-section from being pulled away from the main section, means for locking the mouth-section in its out-position

comprising a piece pivoted at its front end to 40 the mouth-section and being adapted at its rear end to be forced into wedging contact with a suitable abutment in the cabinet, said piece having an operating arm and a rod 45 slidably mounted on the mouth-section, connected at its rear end with said arm and having an exposed finger piece at its front end by which to push and pull the rod.

15. In a phonograph, the combination of 50 a cabinet, a horn comprising a mouth-section and a main section, the main section being located inside the cabinet, and the mouth section outside but being telescopicable into the cabinet when not in use, and door-means combined with the mouth-section 55 convertible from a large size adapted to the mouth of said section to a small size adapted to the mouth of the main section.

16. In a phonograph, the combination of 60 a cabinet, a horn comprising a mouth-section and a main section, the main section being located inside the cabinet, and the mouth section outside but being telescopicable into the cabinet when not in use, and door-means combined with the mouth-section convertible 65 from a large size adapted to the mouth of said section to a small size adapted to the mouth of the main section and means which permits the opening of the large door but not the small door when the mouth-section is in 70 out-position, and which permits the opening of the small door but not the large door when said mouth-section has been telescoped into the cabinet.

In testimony whereof, I have signed my 75 name to this specification, this 20th day of June, 1916.

ROBERT HEAD.
